UNITED STATES PATENT OFFICE.

EMILE RIMAILHO, OF NEUILLY-SUR-SEINE, FRANCE, ASSIGNOR TO HENRY HAMELLE, OF PARIS, FRANCE.

SHOCK-ABSORBING APPARATUS FOR VEHICLES.

No. 861,769.

Specification of Letters Patent.

Patented July 30, 1907.

Application filed November 2, 1906. Serial No. 341,724.

To all whom it may concern:

Be it known that I, EMILE RIMAILHO, a citizen of France, residing at 54 Boulevard Maillet, Neuilly-sur-Seine, France, have invented new and useful Improvements in Shock-Absorbing Apparatus for Vehicles, applicable also to other purposes, of which the following is a specification.

The present invention relates to a shock absorber or hydro-pneumatic buffer specially adapted for the suspension of vehicles but also applicable to other purposes.

The apparatus comprises a closed cylinder in which air is confined above a liquid and a piston guided and movable with regard to each other. Said piston and cylinder are provided with means for limiting their relative movement and the piston is so constructed as to afford a guidance for the coating part of the cylinder and to contain lubricant. The piston is also provided with a movable portion serving as a valve for filling and emptying the casing and further the two parts of the piston are adapted to close the joint between the whole piston and the casing above referred to.

An auxiliary chamber or chambers for containing the liquid is or are provided so that the apparatus may be arranged in a horizontal, vertical or intermediate position as hereinafter explained.

Several forms of apparatus constructed according to this invention are presented in the annexed drawing in which.

Figure 1 is an elevation showing the application to a vehicle spring of the first form of construction shown in sectional elevation in Fig. 2. Fig. 3 is a longitudinal section of a second form of construction and Figs. 4 and 5 show a third form in longitudinal section and cross section on line A—A of Fig. 4 respectively.

The hydro-pneumatic buffer comprises essentially two elements: viz. a cylinder or closed casing *g* forming an accumulator reservoir in which the compressed air is confined above a suitable liquid. This cylinder is provided with a single aperture for passage of a specially constructed piston in two parts forming the second element. The cylinder is so constructed as to limit the outward movement of the piston.

The latter comprises peripheral portions *a*—*f* forming an annular chamber the width of which corresponds to the thickness of the cylinder *g* or in other words the interior diameter of *a* and exterior diameter of *f* correspond respectively to the exterior and interior diameters of the cylinder *g*. The latter is thus guided in the chamber formed by the peripheral portions *a*—*f* of the piston. A flange *h* on the cylinder forms an abutment for an inturned edge *n* of the exterior part *a* of the piston to limit outward movement of the latter, the inward movement being limited by the depth of the

chamber *c*. The latter not only serves as a guide for the relative movement of the cylinder and piston, but at the same time forms a receptacle for lubricant.

In the form shown in Figs. 1 and 2 the diameter of the exterior piston part *a* is enlarged at the upper part to form at this part between the exterior of the cylinder *g* and the interior of piston part *a* a chamber *d* in which the lubricant may pass. The chambers *c* and *d* communicate with each other by means of grooves *b* in the wall *a* of the piston. If on one hand the relative guiding and retention of the cylinder and piston is due to the construction of the peripheral parts of the piston in the form of an annular chamber, the employment of the closed casing *g* is rendered possible by the construction of the axial portion of the piston in the form of a valve which permits of filling said casing with compressed air and liquid. This axial part is adapted to be thus advantageously utilized by the formation of a preferably movable head which forms a closure for the joint between the whole piston and the wall of the cylinder *g*.

In the form shown in Fig. 2 the axial part of the piston is formed as a hollow shaft 1, the closed inner end of which is provided with openings 5 and splayed to form of head or flange 2. An intermediate partition 10 forms a guide for a valve 6 normally held against said partition by a spring 7 located in the chamber 8. A screw threaded portion 9 at the outer extremity of the hollow shaft 1 permits of connecting a union for the filling of the cylinder *g*, and on said exterior end is screwed a nut 11 for which a housing 12 is made in the end of the piston. The joint proper may consist of a cup leather 4 on which the splayed head 2 has a clamping action by means of a ring 3 of rubber or the like. The two parts of the piston *a* and *f* are relatively movable so that they may clamp between them the joint 3—4 formed between the movable piston and the cylinder *g*. This clamping action is produced partly by screwing up the nut 11 and is automatically completed by the pressure of liquid on the head 2. The buffer thus constructed is very compact and perfectly tight and may be rendered anti-vibratory if the cylinder *g* is divided into two chambers *s* and *t* by an intermediate partition *k* located in a central orifice *m* and in which is guided a valve *p* provided with apertures *r*. In order to pass from the chamber *s* into the chamber *t* the liquid raises the valve *p* from its seat formed by the surface of the partition *k*. Since the chamber *t* contains compressed air above the liquid therein the valve is normally held on its seat and the liquid can only pass slowly through the apertures *r*; the movement of the liquid taking place at unequal speeds in the two directions the valve *p* acts as an anti-vibratory valve.

For convenience of the application to a vehicle spring, the two elements of the buffer viz. the piston *a*—*f* and cylinder *g* may be provided with gudgeons *u* and axles *v* or both with gudgeons for connection to the 5 wheel axle and to the spring respectively.

The two elements of the buffer instead of being disposed on a vertical axis, may be on a horizontal or inclined axis the essential condition being that the 10 chamber *g* contains liquid and air so that in all positions, the chamber *s* is full of liquid whereby the valve *p* and the joint are constantly covered thereby.

In the form shown in Fig. 3 where the two elements are arranged horizontally the cylinder *g* is provided at its upper part with a box *x* in which the air is confined 15 whatever may be the position of the piston *a*—*f* with regard to the cylinder *g*.

In the form shown in Figs. 4 and 5, the cylinder *g* is provided with two symmetrical boxes *x* and *y* communicating by conduits *z* which also connect them to 20 the cylinder proper, or as shown more clearly in Fig. 5 an annular extension surrounds the cylinder *g*. In both forms it is sufficient to so choose or calculate the proportions of the chambers *x*—*t* and *x*—*y* as well as the 25 quantities of liquid and air in the closed accumulator in order that the buffer should be reversible and may be arranged as shown in the figures or inclined or even placed vertically with the piston at the lower part.

A similar reversible buffer may be mounted between two rotatable members and rotate through an angle of 300° while preserving its normal action.

Having now described my invention, what I claim as new and desire to secure by Letters Patent is:

1. A shock absorber or hydro-pneumatic buffer for vehicle suspension or other purposes comprising a closed casing or cylinder *g* in which compressed air is confined above the liquid,—in combination with a plunger-piston formed of a sleeve *f* capped by the closed cylinder,—a hollow shaft *1* arranged in the axis of the sleeve *f* and provided with a splayed head *2*,—a filling and emptying valve (5, 6, 7, 8) for the cylinder *g* located within the hollow shaft *40* 1,—and a device (3, 4) forming a joint between the plunger and the casing and clamped by the head *2* of the hollow shaft *1*, substantially as described and for the purpose set forth.

2. A shock absorber or hydro-pneumatic buffer for vehicle suspension or other purposes comprising a closed casing or cylinder *g*, a plunger-piston *f* which penetrates in said closed cylinder, a casting *a* solid with the plunger and surrounding the closed cylinder, extensions or boxes made solid and communicating with the closed cylinder in which are located the liquid and air confined above same, and a valve controlling said communication, substantially as described and for the purpose set forth.

In testimony whereof I have signed my name to this specification in the presence of two subscribing witnesses.

EMILE RIMAILHO.
